W. M. MYERS

REFRIGERATOR

Filed Dec. 10, 1920

William M. Myers INVENTOR.

BY

Emm^on Albreker & Woolard ATTORNEYS.

UNITED STATES PATENT OFFICE.

WILLIAM M. MYERS, OF ST. JOSEPH, MISSOURI, ASSIGNOR TO THOMAS H. GILL, OF MILWAUKEE, WISCONSIN.

REFRIGERATOR.

Application filed December 10, 1920. Serial No. 429,793.

To all whom it may concern:

Be it known that I, WILLIAM M. MYERS, a citizen of the United States, residing at St. Joseph, county of Buchanan, and State 5 of Missouri, have invented new and useful Improvements in Refrigerators, of which the following is a specification.

My invention relates to improvements in refrigerators of that type in which the circulation of an elastic fluid is automatically 10 or thermostatically controlled, and it particularly relates to the portions of such apparatus which are designed to be installed in the refrigerating chamber.

15 The objects of my invention are to provide highly efficient apparatus for the desired purpose; to provide a more reliable thermostatic control than any heretofore devised; to provide a simple, compact, and 20 durable structure, peculiarly suited to the requirements of domestic refrigerating plants, where economy of space is one of the primary requisites; to provide apparatus in which air may be successfully used as 25 the refrigerating medium or elastic fluid, thereby providing perfectly safe installations; and to provide a sanitary refrigerator requiring minimum care and attention.

In the drawings:

30 Figure 1 is an elevational sectional view, drawn generally to a plane common to the inlet and outlet ports of the circulatory coil, the main inlet for the refrigerant, and the pressure reducing valve.

35 Figures 2 and 3 are cross sectional views taken respectively on lines 2-2 and 3-3 of Figure 1.

Figure 4 is a plan view of the valve casting with the cap removed.

40 Figure 5 is a plan view of the lower end cap for the condensing chamber.

Like parts are identified by the same reference characters throughout the several views.

45 The refrigerant is delivered to the condensing chamber 1 thru a duct 2. The chamber 1 is closed at its lower end by a cap 3 having an outlet port 4 normally closed by a needle valve 5, connected with a 50 float 6 guided between the projections 7 and adapted to be lifted by water, when the latter accumulates in sufficient quantity, thereby opening the valve and allowing the water

to pass through the outlet port 4 to any suitable drain pipe that may be connected 55 thereto.

A duct 10 leads downwardly in the condenser chamber 1, and its lower end is connected with an apertured projection 11 suitably bored at 12 and 13 to receive the end 60 of the duct 10 and the lower end of the coiled pipe 14, as shown. The pipe 14 is coiled about the chamber 1 between it and an outer jacket 16, and its upper end is coupled at 17 to the valve casing member 65 18 to afford communication with the port 19 and cavity 20 therein. From this cavity 20 the fluid may pass thru the port 22 to the cavity 23 when the valve 25 is open, whereupon it is free to pass thru the openings 26 70 leading from this cavity to the jacket space, within which the coils are located, and downwardly along the coils to the lower end of the jacket, where it may pass to the exterior, or to an outlet duct if desired. No 75 outlet duct is illustrated, for if air is used as the refrigerant, no such duct will be required.

The valve 25 is connected by a stem 30 with a piston or diaphragm head 31 seated 80 within the casing member 32, the upper end of which is closed by a diaphragm 33 upon the outer face of which a ring 34 is seated, the ring being covered by a cap 35 to form an air chamber 36 above the diaphragm. 85 Fluid under pressure in this chamber tends to hold the valve 25 to its seat, but when this pressure is relieved the piston, (diaphragm 32 and piston head 31), are pushed upwardly by a spring 37 interposed between shoulder 38 and a cup shaped seating 39 on the guide sleeve 40 through which the valve stem 30 passes.

The elastic fluid is supplied to the chamber 36 from the main inlet duct 2 through the by-pass 44, pressure reducer 45, thermostatically controlled chamber 46 and duct 47. The heat actuated bar or member 48 of the thermostat is connected with a valve at 49, which, when opened, allows the air to escape from chamber 36, thereby permitting the coiled spring 37 to open the valve 25, as above explained. It is the function of the pressure reducer to lower the air pressures in pipe 44 to the point where the thermostatic device can control them. 100 105

The specific structure of the pressure reducer or reducing valve 45 is not essential, any ordinary reducing valve capable of accurately maintaining the desired normal pressure in chamber 36 being adapted for my purpose. In the construction shown the fluid is by-passed around an interior diaphragm chamber 50 thru the duct 51 when the needle valve 52 is open. The differential diaphragms 53 and 54, working in co-operation with the interposed spring 55, tend to retract the larger diaphragm 54 and open the needle valve 52. But as the pressure in chambers 56 and 36 builds up it eventually becomes effective to press diaphragm 54 downwardly and actuate the valve 52 to its seat thru the stem 58, against the pressure spring 55 and the fluid pressure on the smaller diaphragm 53.

To prevent the main valve 25 from freezing, I provide another by-pass duct 60 which leads from the main inlet 2 thru an opening 61 in the casing member 32 to an interior passage 62 in the stem 30 leading to a port 64 in the point of the valve, thereby providing means for circulating fluid thru the valve to the port 22 at normal temperature of the compressed fluid. The duct 60 is preferably provided with a coil 65, and is formed of material which is sufficiently flexible to allow the necessary movement at the point of connection with the valve stem.

It will be understood that the present invention relates particularly to such portions of a refrigerating mechanism as are designed to be installed in a refrigerating chamber, such as a household ice-chest or the like. The means for compressing the refrigerant, and the means for cooling the compressed refrigerant to atmospheric temperature, being well known in the art, are not shown herein.

The function of the chamber 1 and the worm or helically coiled pipe 14 is to provide means for gradually chilling the air prior to its expansion, whereby the last vestiges of moisture remaining in the air may be eliminated. To this end the air is passed through the chamber 1 which is a comparatively heavy structure, and is not particularly adapted for delivery of heat through its walls. The cooler air within the casing 16, however, will keep chamber 1 at a sufficiently low temperature so that most of the water carried by the air passing therethrough will condense and cool in the bottom of said chamber whence it may be delivered by the float valve. Air is taken from said chamber at a sufficient height therein so that the danger of water being taken into pipe 10 is practically nil. Thereafter, the air passes through the coil 14 and tends to assume the temperature of the refrigerated air in casing 16, whereby any remaining vapor is condensed and runs by gravity to the lowest

point of tube 14 where a suitable duct is provided through which said water may be drawn off at intervals, as by drain cock 14'.

When it reaches the reducing valve 25, the compressed air will be at a relatively low temperature, and obviously the temperature thereof will be further reduced by expansion through the valve. Any moisture remaining at this point might tend to congeal and form snow in sufficient quantities to obstruct the operation of the valve were it not for the admission through the hollow stem of the valve of uncooled air from the supply main which will be admitted in small quantities, and will tend to flow upwardly across the face of the valve itself, and thereby to maintain the valve substantially at atmospheric temperature. The advantage of the particular structure shown in the drawings is that when the valve is closed the pressure of the air within the by-pass duct 62 and within the duct 22, leading from the cooling coils, will be equalized and by the by-pass will become operative only when the pressure is unbalanced by the opening of the valve.

The thermostatic device shown in Figure 1 is preferably located within the refrigerator or chamber to be cooled by the operation of the mechanism of this invention. The arrangement of the heat actuated bar 48 of the thermostat is such with reference to valve 49 that when the temperature reaches a predetermined degree within the refrigerator, the valve 49 will be opened and the air within pipe 47 and chamber 36 will be released. Spring 37 will thereupon open valve 25 until the low temperature within the refrigerator is restored. As the temperature drops, the thermostatic devices will gradually close valve 49 until finally the pressure will build up within pipe 47 and chambers 56 and 36 to the full extent permitted by the regulating valve, shown at the left in Figure 1. The pressure so established closes valve 25 and thus stops all action of the device until the temperature within the refrigerator again falls to the extent necessary to open valve 49.

I claim:—

1. Refrigerating apparatus including the combination with means for supplying fluid under pressure, of a ported expansion chamber, a worm in communication with the source of fluid supply and connected at its end with the port of the chamber, the worm being within the thermal influence of the chamber, a valve provided with a stem and adapted to close said port, a diaphragm operatively connected with the stem for valve actuation, means for diverting a portion of the fluid under reduced pressure and applying the pressure to the diaphragm, and a thermostat adapted to control the amount of pressure so applied.

2. In a refrigerating apparatus having an expansion chamber and means for supplying a fluid thereto under pressure, the combination of a valve controlling the admission of fluid to the chamber, a tubular stem for the valve, and means for by-passing a portion of the fluid thru the stem of the valve. 5
3. In a refrigerating apparatus having an expansion chamber and means for supplying a fluid thereto under pressure, the combination of a ported valve controlling the admission of fluid to the chamber, of means for cooling a portion of the fluid before it reaches the chamber, and means for by-passing another portion of the fluid through the port in said valve, whereby circulation of uncooled fluid through said valve is maintained when the valve is open. 10
4. In a refrigerating apparatus having an expansion chamber and means for supplying a fluid thereto under pressure, the combination of a valve controlling the admission of fluid to the chamber, means for cooling a portion of the fluid before it reaches the chamber, means for by-passing an uncooled portion of the fluid through the valve in the direction of the high pressure side thereof; and thermostatically controlled means for utilizing the pressure of another portion of said fluid to operate the valve in one direction. 15
5. In a refrigerating apparatus including an expansion chamber provided with an inlet passage and means for supplying a compressed fluid to the chamber thru the passage, the combination of a valve controlling the delivery of fluid from the passage to the chamber and provided with a by-pass thru its face, a tubular valve stem in communication with the passage thru the by-pass, and a tube connecting the valve stem with the source of fluid supply. 20
6. In a refrigerating apparatus including an expansion chamber provided with an inlet passage, means for supplying a compressed fluid to the chamber thru the passage, and means for conducting the fluid into heat transmitting association with the chamber before it enters the passage, the combination of a valve controlling the delivery of fluid from the passage to the chamber and provided with a by-pass thru its face, a tubular valve stem in communication with the passage thru the by-pass, and a tube connecting the valve stem with the source of fluid supply, whereby the opening of the valve will reduce the pressure of the pre-cooled fluid in the passage allowing the delivery of uncooled fluid thru the by-pass in the valve to warm the same. 25
7. A refrigerating apparatus including an expansion chamber, means for supplying fluid under pressure thereto, a valve controlling fluid delivery to the chamber, and means for by-passing a portion of the fluid thru the valve, fluid delivery thru the by-pass taking place toward the pressure side of the valve. 30
8. Refrigerating apparatus including means for supplying a compressed fluid, a ported expansion chamber, a ported condensing chamber in communication with said fluid supplying means and with said expansion chamber, a float valve controlling the port in the condensing chamber, an expansion valve controlling the admission of fluid through the port in the expansion chamber, and means for leading to a point adjacent the face of said valve a portion of the fluid admitted through said fluid supplying means. 35
9. Refrigerating mechanism including the combination with an expansion chamber, means for supplying compressed fluid, and means for subjecting said fluid to the thermal influence of said chamber, whereby vapors carried in the fluid may be condensed; of an expansion valve controlling the admission of fluid to the expansion chamber, and a by-pass duct adapted to deliver fluid from said supplying means to a point adjacent the face of said expansion valve upon the high pressure side thereof. 40
